UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

PRINTING-MACHINE.

945,761.

Specification of Letters Patent. Patented Jan. 11, 1910.

Application filed February 9, 1909. Serial No. 476,965.

To all whom it may concern:

Be it known that I, ALBERT B. DICK, a citizen of the United States, residing at Lake Forest, in the county of Lake and State of Illinois, have invented a certain new and useful Improvement in Printing-Machines, of which the following is a specification.

This invention relates to printing-machines and is directed to the provision of a machine adapted for office use, which can be run at comparatively high speed by an unskilled operator, and with which prints may be produced in close imitation of typewritten work.

The invention involves the provision of a printing-machine having a bed on which a form of type is supported, an ink-ribbon coacting with the printing faces of the type, a rotatable pressure-roller, and means, such as endless carriers, for moving the pressure-roller in one direction over the type and in coaction therewith to effect the printing, and then in the other direction on the opposite side of the type-form and the bed therefor to return the roller to initial position.

One object of the invention is to provide in a machine of this type improved operating mechanism whereby the machine may be operated either manually or from a source of power, the devices by which this is accomplished being so arranged as to make the structure very compact and to permit of convenient operation of the machine.

Another object of the invention is to provide an improved mechanism for delivering the sheets after they have been imprinted upon. This delivery mechanism includes a device adapted to engage the rear edge of a sheet after the latter has been imprinted upon and push the sheet ahead of it away from the printing position, this delivery device being arranged to reciprocate and being actuated in one direction by the mechanism for moving the pressure-roller and then automatically released and retracted by a spring.

The preferred embodiment of the invention is illustrated in the accompanying drawings, in which—

Figure 1 is a plan view of the machine broken away and sectioned in part; Fig. 2 is an elevation broken away in part; Fig. 3 is a view in elevation of portions of the operating mechanism taken just inside the frame-member shown in Fig. 2; Fig. 4 is a sectional elevation of the motor-driven operating de-

vice; Fig. 5 is a sectional elevation of the manual operating device; and Fig. 6 is a detail view in section on line 6—6 of Fig. 5.

Referring to these drawings, the machine consists of a base A, on which are mounted side-frames B, B', disposed parallel to each other. Extending between the side-frames and mounted for rotation in bearings therein, are two shafts C, C', connected together, so as to operate in unison, and one provided with a handle c for turning the two shafts. These shafts carry eccentrics, upon which is mounted the bed c' for supporting the chase c² in which the type-form c³ is locked in the ordinary manner. An arc-shaped member c⁴ is mounted upon the side-frame B and provided with a number of holes into any one of which a pin c⁵ may be inserted to facilitate positioning the handle c. The mechanism above described permits of raising or lowering the bed c' and the form of type thereon, so as to accurately position the same, but it will be understood that any other suitable mechanism for accomplishing this purpose may be provided. An ink-ribbon D overlies the printing faces of the type c³, its ends being wound on spools d mounted for rotation in bearings carried by the side-frames of the machine. A pressure-roller E is adapted to coact with the page-form of type to effect the printing. This roller E is mounted for rotation in bearings formed in links of two endless carriers e here shown as chains, each chain lying adjacent to one of the side-frames.

A shaft e' is mounted for rotation in bearings formed in the side-frames and carries two sprocket-wheels e² on which the chains e run. At the other end of the machine are two stub-shafts, e³, upon each of which is rotatably mounted a similar sprocket-wheel for one of the chains e. The side-frames B and B' may each be provided with inwardly extending flanges e⁴ and e⁵, and the roller E may have disks upon the ends thereof adapted to travel between these flanges so as to cause the roller E to move in a horizontal plane while passing over the type-form. On one end of the shaft e' is a pinion f meshing with a gear f' adapted to be rotated by a manually operated handle F. Between the handle F and the gear f' is a clutch which permits the gear f' to rotate independently of handle F when the machine is being driven by power. Referring to Figs. 5 and 6, it

will be seen that the gear f' has a hub f^2 on the side thereof adapted to be received within a similarly shaped recess formed in the end of the handle F . On the side of handle F is a pin f^3 forming a pivot for a pawl f^4 , the end of which is pressed by a spring f^5 in a direction to carry it through a cut-away portion in the handle F and into a notch in the hub f^2 , as shown in Fig. 6. It will be seen that handle F , when rotated in a counter-clockwise direction as seen in Fig. 6, will cause rotation of hub f^2 and gear f' , thereby operating the sprockets e^2 and carriers e , but that gear f' and hub f^2 may be rotated in this direction without causing rotation of handle F . On the other side of the machine, the shaft e' is extended through its bearing in the side-frame B' and a worm-gear H is loosely mounted on this end of shaft e' . Gear H has a flange h on the side thereof, the inner surface of which is conical-shaped. Splined on shaft e' between the gear H and the side-frame B' is a clutch-member h' having a conical-shaped surface corresponding to the interior surface of flange h and provided with pads h^2 of such material as will give a good frictional engagement between the clutch-member h' and the flange h . The clutch-member h' has a circumferential groove h^3 adapted to receive pins on the ends of bifurcated arms h^4 of a lever h^5 pivotally mounted upon the side-frame B' . The clutch-member h' is normally held away from the gear H in the position shown in Fig. 4, by a spring h^6 arranged between the side-frame B' and the lever h^5 ; but the clutch-member may be moved into engagement with the gear H by means of a handle I pivotally mounted upon the side-frame B at the other side of the machine, in a position convenient for the operator. The shaft i upon which handle I is mounted has a crank i' to which is pivotally connected one end of a connecting rod i^2 , the other end of which is pivotally connected to the lever h^5 . The gear H meshes with a worm i^3 on the shaft i^4 of an electric motor i^5 . It will be seen that when the motor i^5 is in operation, it may be caused to actuate the machine by merely turning handle I in a direction to move the clutch-member h' against the tension of spring h^6 into engagement with the gear H . Thus by manipulating the handle I , the machine may be operated by the motor continuously or intermittently, and in the latter case by movements of any extent desired, and by releasing the handle I the motor is thrown out of driving relation and the machine may be operated as is desired by the handle F .

The adjacent edges of the flanges e^5 on the side-frames of the machines are formed, as shown in Fig. 1, to provide ways J upon which guides j, j' may slide, and a shaft j^2 extends between these guides and is mounted

for rotation in bearings formed therein. Secured upon the shaft j^2 is a hook-shaped member j^3 (Fig. 3), which is adapted to engage the rear edge of a sheet after the latter has been imprinted upon and to deliver the sheet. A spring j^4 acts upon the shaft j^2 in a direction to depress the free end of the hook j^3 and hold the hook in the position in which it is shown in Fig. 3, in which position further rotational movement of shaft j^2 is prevented by a suitable stop.

On the guide j is a depending finger K adapted to be engaged by a pin k carried by a plate k' which is secured to the chain e and which plate is extended downwardly so as to provide a portion adapted to travel upon the flange e^4 to cause pin k to move in a horizontal plane. Thus when pin k is carried into engagement with finger K by the chain e , the continued movement of the chain and pin will cause movement of finger K , guides j and j' and the parts carried by the guides, and during this movement a pin k^2 on an arm k^3 secured to the shaft j^2 will engage and be depressed by a cam-surface on the end of a strip k^4 secured upon the side-frame B . When pin k^2 is depressed thus, the shaft j^2 is rotated somewhat, so as to raise the free end of the hook j^3 , and this raising of the end of the hook occurs just after the latter has engaged the edge of a sheet and before the end of the hook comes up to the edge of the type-form. In order that this movement of the hook may be made to take place at the proper time, the strip k^4 is provided with longitudinal slots, through which screws k^5 extend, so that by loosening the screws the strip k^4 may be adjusted in the direction of its length. After the rod j^2 has been carried to a position beyond the end of the type-form, the pin k is carried downwardly by the portion of the chain e to which it is affixed traveling around the sprocket e^2 , and the pin k at this time disengages the finger K , as indicated by the dotted lines at the right of Fig. 3. At this time, the delivery of the printed sheet has been accomplished, and means are provided for returning the delivery device to its initial position.

The guide j has affixed thereto one end of a cord L , the other end of which is wound upon a drum l which is loose upon a short shaft l' rotatable in a bearing formed in a piece l^2 projecting from the side-frame B . Pivotally mounted on the drum is a pawl l^3 pressed by a spring against the teeth of the ratchet-wheel l^4 mounted upon the shaft l' . To the shaft l' is fixed one end of a spiral spring l^5 , the other end of which is fixed to a pin l^6 upon a plate l^7 which is rigidly secured to the arm j^2 . Thus, when the delivery device is moved to the left in Fig. 1, the cord L turns the drum l and by means of the pawl and ratchet winds up the spring l^5 , 130

so that this spring is under considerable tension when the delivery device reaches the end of its movement; then as the delivery device is released by the pin k , the spring 5 acting through the drum l and the cord L , retracts the delivery device to its initial position at the right of the machine, as shown in Fig. 1.

The operation of the delivery mechanism 10 will be readily understood from the foregoing description. The roller E and the pin k are so positioned upon the chains that the pin engages finger K just after the roller E completes the printing of the impression, 15 and as the roller is returning beneath the bed to its initial position the hook j^3 is moved to the left in Fig. 1, engages the rear edge of a sheet, is raised by the coaction of pin k^2 and cam k^4 and pushes the sheet 20 ahead of it from the printing position to a delivery-tray P . When the delivery of the sheet is accomplished, the finger K is released and the hook j^3 is returned to its initial position by the spring-actuated drum 25 before the roller E is brought upwardly into position for printing another impression. The tension on the spring l^5 may be regulated by means of a suitable key applied to the squared end of shaft l' , it being only 30 necessary, in order to increase the tension of the spring, to hold drum l with one hand while turning the shaft l' with the other.

Having now described my invention, what I claim as new therein and desire to secure 35 by Letters Patent is as follows:—

1. A printing-machine having a bed, a form of type thereon, an ink-ribbon overlying the printing faces of the type, a rotatable pressure-roller adapted to coact 40 with the type, means for moving said bed and roller relatively, a delivery device adapted to engage a sheet while the same is in printing position and move the sheet therefrom, means for moving said device to deliver the sheet, and means for returning said 45 device to initial position independently of the relative movement of said bed and pressure-roller, substantially as set forth.

2. A printing-machine having a bed, a form of type thereon, an ink-ribbon overlying the printing faces of the type, a rotatable pressure-roller adapted to coact 50 with the type, means for moving said bed and roller relatively, a delivery device adapted to engage the rear edge of a sheet while the same is in printing position and move the sheet before it, means for moving said device to deliver the sheet, and means for returning said device to initial position independently 55 of the relative movement of said bed and pressure-roller, substantially as set forth.

3. A printing-machine having a normally stationary bed, a form of type thereon, a rotatable pressure-roller movable bodily in co- 60

action with the type, a delivery device adapted to engage a sheet while the same is at rest in printing position and move the sheet therefrom, means for moving said device in correspondence with the movement of said 70 roller to deliver a sheet, and means for returning said device to initial position independently of the movement of said roller, substantially as set forth.

4. A printing-machine having a normally 75 stationary bed, a form of type thereon, a rotatable pressure-roller movable bodily in coaction with the type, a delivery device adapted to engage the rear edge of a sheet while the same is at rest in printing position and move the sheet from before it, means for moving said device in correspondence with the movement of said roller to deliver a sheet, and means for returning said device to initial position independently of the movement of said 80 roller, substantially as set forth.

5. A printing-machine having a bed, a form of type thereon, an ink-ribbon overlying the printing faces of the type, a rotatable pressure-roller adapted to move in 90 coaction with the type, a delivery device adapted to engage the rear edge of a sheet and move the same before it from printing position, means for moving said device in correspondence with the movement of said 95 roller to deliver a sheet, and means for returning said device to initial position independently of the movement of said roller, substantially as set forth.

6. A printing-machine having a bed, a 100 form of type thereon, an ink-ribbon overlying the printing faces of the type, a rotatable pressure-roller, endless carriers on which said roller is mounted, means for actuating said carriers to move the roller in 105 one direction in coaction with the type to effect the printing and in the opposite direction on the other side of the type and bed to return the roller to initial position, a delivery device adapted to engage a sheet and move the same from printing position, means for moving said device in correspondence with the movement of said roller to deliver a sheet, and means for returning said device to initial position independently of the 110 movement of said roller, substantially as set forth.

7. A printing-machine having a bed, a form of type thereon, an ink-ribbon overlying the printing faces of the type, a rotatable pressure-roller adapted to move in 120 coaction with the type, a delivery device adapted to engage a sheet and move the same from printing position, means for moving said device in correspondence with the 125 movement of said roller to deliver a sheet, means for moving said delivery device away from the type immediately after it engages the sheet, and means for returning said delivery device to its initial position inde- 130

pendently of the movement of said roller, substantially as set forth.

8. A printing-machine having a bed, a form of type thereon, an ink-ribbon overlying the printing faces of the type, a rotatable pressure-roller, endless carriers on which said roller is mounted, means for actuating said carriers to move the roller in one direction in coaction with the type to effect the printing and in the opposite direction on the other side of the type and bed to return the roller to initial position, a delivery device for engaging a sheet and moving the same from printing position, a projection on one of said flexible carriers for engaging said delivery device and moving the same, said projection being adapted to automatically release the delivery device, and means for returning the delivery device to initial position, substantially as set forth.

9. A printing-machine having a bed, a form of type thereon, an ink-ribbon overlying the printing faces of the type, a rotatable pressure-roller, endless carriers on which said roller is mounted, means for actuating said carriers to move the roller in one direction in coaction with the type to effect the printing and in the opposite direction on the other side of the type and bed to return the roller to initial position, a delivery device for engaging a sheet and moving the same from printing position, a projection on one of said flexible carriers for engaging said delivery device and moving the same, said projection being adapted to automatically release the delivery device, means for returning the delivery device to initial position, and means for moving the delivery device away from the type immediately after it engages the sheet, substantially as set forth.

10. A printing-machine having a bed, a form of type thereon, an ink-ribbon overlying the printing faces of the type, a rotatable pressure roller, means for moving the roller in coaction with the type, a delivery device adapted to engage the rear edge of a sheet and move the same before it from printing position, means for moving said device in correspondence with the movement of said roller, and a spring put under tension during the movement of said delivery device when the latter is delivering the sheet and adapted to return the delivery device to its initial position, substantially as set forth.

11. A printing-machine having a bed, a form of type thereon, an ink-ribbon overlying the printing faces of the type, a rotatable pressure-roller adapted to move bodily in coaction with the type, a delivery device movable to engage a sheet when the same is at rest in printing position and deliver the sheet, a part movable with said roller and arranged to engage said delivery device and move the same, said part being

adapted to automatically release the delivery device, and means for returning the delivery device to initial position independently of the movement of said roller, substantially as set forth.

12. A printing-machine having a bed, a form of type thereon, an ink-ribbon overlying the printing faces of the type, a rotatable pressure-roller, endless carriers on which said roller is mounted, means for actuating said carriers to move the roller in one direction in coaction with the type to effect the printing and in the opposite direction on the other side of the type and bed to return the roller to initial position, a delivery device for engaging a sheet and moving the same from printing position, means for moving said delivery device in accordance with the movement of said carriers to deliver a sheet, and a spring put under tension during the movement of the delivery device and adapted to return said device to initial position, substantially as set forth.

13. A printing-machine having a bed, a form of type thereon, an ink-ribbon overlying the printing faces of the type, a rotatable pressure-roller, endless carriers on which said roller is mounted, means for actuating said carriers to move the roller in one direction in coaction with the type to effect the printing and in the opposite direction on the other side of the type and bed to return the roller to initial position, a delivery device for engaging a sheet and moving the same from printing position, a projection on one of said flexible carriers for engaging said delivery device and moving the same, said projection being adapted to automatically release the delivery device, means for moving the delivery device away from the type immediately after it engages the sheet, and a spring put under tension during the movement of said delivery device when the latter is delivering a sheet and adapted to return the delivery device to its initial position, substantially as set forth.

14. A printing-machine having side-frames, a bed between the same, a type-form on said bed, a roller adapted to move bodily over the type and in coaction therewith, ways formed on said side-frames, a delivery device adapted to slide upon said ways and to engage a sheet while the same is at rest in printing position and deliver the sheet, means for moving said device in one direction, and a spring connected to said device and put under tension during the movement thereof, said spring being adapted to return said device to initial position, substantially as set forth.

15. A printing-machine having a normally stationary bed, a form of type thereon, an ink-ribbon overlying the printing faces of the type, a rotatable pressure-roller, endless carriers on which said roller is mounted,

- means for actuating said carriers to move the roller in one direction in coaction with the type to effect the printing and in the opposite direction on the other side of the 5 type and bed to return the roller to initial position, a delivery device adapted to engage the rear edge of a sheet and move the same before it from printing position, means for moving said device in correspondence with the movement of said roller to deliver a 10 sheet, and means for returning said device to initial position independently of the movement of said roller, substantially as set forth.
- 15 16. A printing-machine having a bed, a form of type thereon, a rotatable pressure-roller movable bodily in coaction with the type, a delivery device movable over the form of type to engage a sheet and move the same from printing position, a part moving with said roller and adapted to engage said delivery device and move the same over the form of type to deliver a sheet, said
- part being adapted to automatically release said device, and means for returning the delivery device to initial position, substantially as set forth. 25
17. A printing-machine having a bed, a form of type thereon, a rotatable pressure-roller movable bodily in coaction with the type, a delivery device for engaging the rear edge of a sheet and moving the same before it from printing position, a part moving with said roller and adapted to engage said delivery device and move the same to 30 deliver a sheet, said part being adapted to automatically release said device, and means for returning the delivery device to initial position, substantially as set forth. 35

Correction in Letters Patent No. 945,761.

It is hereby certified that in Letters Patent No. 945,761, granted January 11, 1910, upon the application of Albert B. Dick, of Lake Forest, Illinois, for an improvement in "Printing-Machines," an error appears in the printed specification requiring correction as follows: Page 3, line 81, the word "from" should be stricken out; and that the said Letters Patent should be read with this correction therein that the same may conform to the record of the case in the Patent Office.

Signed and sealed this 8th day of February, A. D., 1910.

[SEAL.]

E. B. MOORE,
Commissioner of Patents.

- means for actuating said carriers to move the roller in one direction in coaction with the type to effect the printing and in the opposite direction on the other side of the 5 type and bed to return the roller to initial position, a delivery device adapted to engage the rear edge of a sheet and move the same before it from printing position, means for moving said device in correspondence with the movement of said roller to deliver a 10 sheet, and means for returning said device to initial position independently of the movement of said roller, substantially as set forth.
- 15 16. A printing-machine having a bed, a form of type thereon, a rotatable pressure-roller movable bodily in coaction with the type, a delivery device movable over the form of type to engage a sheet and move the same from printing position, a part moving with said roller and adapted to engage said delivery device and move the same over the form of type to deliver a sheet, said
- part being adapted to automatically release said device, and means for returning the delivery device to initial position, substantially as set forth. 25
17. A printing-machine having a bed, a form of type thereon, a rotatable pressure-roller movable bodily in coaction with the type, a delivery device for engaging the rear edge of a sheet and moving the same before it from printing position, a part moving with said roller and adapted to engage said delivery device and move the same to 30 deliver a sheet, said part being adapted to automatically release said device, and means for returning the delivery device to initial position, substantially as set forth. 35
